UNITED STATES PATENT OFFICE.

NATHAN GOLDSMITH, OF NEWARK, NEW JERSEY, ASSIGNOR TO L. GOLDSMITH & SON, OF NEWARK, NEW JERSEY, A FIRM COMPOSED OF DAVID OSTERWEIL, NATHAN GOLDSMITH, SYDNEY OSTERWEIL, AND LEON OSTERWEIL.

GARMENT-SUPPORT FOR WARDROBE-TRUNKS.

1,169,632.

Specification of Letters Patent. Patented Jan. 25, 1916.

Application filed May 10, 1915. Serial No. 27,021.

To all whom it may concern:

Be it known that I, NATHAN GOLDSMITH, a citizen of the United States, and a resident of Newark, in the county of Essex and State 5 of New Jersey, have invented certain Improvements in Garment-Supports for Wardrobe-Trunks, of which the following is a specification.

The objects of this invention are to provide for wardrobe trunks an improved device upon which garments can be hung or supported so as to prevent their being creased or crumpled and which will render them readily accessible; to provide such a support which can remain mounted upon the trunk when the same is opened as at a hotel, or which can be removed from the trunk and placed upon a closet door or the like; to enable the individual hangers or garments 15 thereon to be readily accessible in either case; to secure the various parts against relative displacement during transit of the trunk; to secure a simple and effective construction, and to secure other advantages 20 and results as may be brought out in the following description.

Referring to the accompanying drawings, in which like numerals of reference indicate the same parts throughout the several views, 30 Figure 1 is a perspective view of an open wardrobe trunk containing my improved garment support, the individual hangers being removed for greater clearness; Fig. 2 is a view of a door with the pivoted rack of 35 my improved garment support removed from the trunk and hung thereon for use instead of in the trunk; Fig. 3 is a front elevation of the portion of the trunk to which my improved support is applied, showing the same closed into the trunk as it is for transportation; Fig. 4 is a vertical cross-section of the 40 same taken upon line A—A Fig. 3; Fig. 5 is a vertical cross-section taken on line B—B Fig. 3; Fig. 6 is a detail view of the member 45 mounted upon the trunk body which provides bearings for the pivoting rack; Fig. 7 is a perspective view of a modified construction of garment support with the individual hangers omitted; Fig. 8 is a perspective 50 view of a further modified construction of the member mounted upon the trunk body which provides bearings for the pivoting rack; Fig. 9 is a front elevation of the trunk to which a modified construction of

my support is applied; Fig. 10 is a cross-sectional view of the same taken on a plane substantially parallel with the front of the trunk centrally of the rack and its supporting member; Fig. 11 is a similar cross-sectional view of a further modified construction of support, and Fig. 12 is a similar cross-section of a still further modified construction.

In said drawings, referring to the specific embodiment of the invention as shown in 65 Figs. 1—6 inclusive, 1, 2 indicate hinged sections of a wardrobe trunk to one of which sections as 2, my invention is shown applied. A member 3 here shown as comprising a middle portion 4 adapted to be secured flatwise against the inner wall of the trunk and having ends 5, 6 bent in the same direction into parallel relation and providing bearings, is secured to one corner of the trunk, upon the inner wall thereof and preferably adjacent to its outer edge. The said middle portion 3 of the member is shown flatwise against the longer front side of the trunk with its edge flush with the edge of said side, and one of its ends similarly located with respect to the end wall of the trunk which becomes the top when the trunk is stood on end, as in a hotel. This bearing member is shown in detail in Fig. 6 and it will be noted that its lower end 6 provides a 70 stud 7 projecting parallel to the main portion 4 and in alinement with a similar but longer stud 8 on the other bent end 5. Between these studs is pivoted a rack 9 having a standard 10 which is hollow and adapted 75 to receive the said studs. It will be understood that the said standard is somewhat shorter than the space between the ends 5, 6 of the bearing member, so that when it is slipped onto the long stud 8 as far as possible its other end will receive the stud 7 and sit thereon without detachment of the first-mentioned end from the long stud 8. In order to further facilitate this operation, the long stud 8 is slightly tapered from its 80 extremity toward the bent end 5. From the said standard 10 which is to be understood is substantially vertical when the trunk is stood on end as shown in Fig. 1, a lateral arm projects to a length as great as possible 85 and yet permit the arm to swing into the trunk section as shown in Fig. 3. This arm can obviously be constructed in any suitable 90

manner, but I have shown it of an elongated U-shape with its two ends rigidly fixed to the standard 10 suitably near the end thereof which is uppermost when the trunk is stood up for use, as shown in Fig. 1. This arm 11 has lateral brackets 12, 12 near its opposite ends, said brackets projecting from the arm toward the bottom or back of the trunk section when the arm is swung into the trunk section as shown in Figs. 3 and 4. These brackets may be of any suitable construction, although I have found it convenient to make them of upper horizontal pieces 13 projecting from the upper portion of the U-shape arm 11 and braces 14 extending from said horizontal pieces downward at an incline to the lower portion of said U-shaped arm. Preferably the extremities of the brackets 12 are upturned as at 15, and as shown in Fig. 4 most clearly said upturned ends approach closely enough to the top wall of the trunk section to prevent the standard 10 from being removed from its bearing studs 7, 8 while the pivoted rack is swung into the trunk section. In other words, said pivoted rack can be detached only when swung out of the trunk section, as shown in Fig. 1.

The brackets 12, 12 are long enough to extend substantially the entire depth of the trunk section and therefore they receive a large number of garment hangers 16 one of which is shown in Figs. 3 and 4. These hangers each comprise a cross piece 17 with hooked fingers 18, 18 at the ends thereof adapted to take over the brackets 12, 12, as shown. Preferably the hooks of said fingers are sufficiently deep so that the fingers cannot disengage from the brackets 12, 12 while the same are within the trunk section and underlying the top thereof, as will be obvious from an inspection of Fig. 3. It will be understood that the lower part of the hanger, designated by reference numeral 19 receives the coat or the like, after the fashion of other hangers.

A keeper plate 20 on the side wall of the trunk section opposite that to which the bearing member 3 is secured, is provided with a projecting keeper 21 behind which the end 50 of the pivoted rack 9 or a lug 22 thereon is adapted to lie when in closed position to keep it from inadvertently swinging open or out of the trunk section, it being understood that said pivoted rack can be lifted 55 or sprung over said keeper either to lock the rack in closed position or to release it for opening.

By my improved construction, if the user of the trunk desires to do so, he can remove 60 the pivoted rack 9 from its bearing and hang the same upon a closet door 23 or the like as shown in Fig. 2, and furthermore this can be done with the clothes hangers upon said rack and without removing them. This 65 enables the guest if he so desires to remove

his clothes from the wardrobe trunk and hang them up in his room, and to do the same expeditiously and simply.

In Figs. 7 and 8 I have shown a modified construction of bearing member 24 the same 70 having a pair of ears 25, 25 bent up into parallel relation and adapted to receive the ends 26, 26 of the arms of the U-shaped rack 27. This is a simpler form of pivoting than the preferred construction already described, and obviates the use of the standard 10. In Fig. 8 tubular sockets 28, 28 are provided for the bent ends of the arms of the U-shaped rack, said sockets being formed by rolling up ears projecting from the edge 80 of the bearing member 29.

In Figs. 9 and 10 I have shown the form 85 of a pivoted rack in which an elongated loop-like arm 30 is pivoted by means of a transverse screw 31 extending through one end of said arm and also the parallel ends 32, 32 of a bearing member 33 secured to the trunk section 34. The said screw 31 has a large milled head so that it can be readily withdrawn and put back for detachment of the rack, and the outer swinging end of the rack is supported by a brace 35 inclined downward toward the side wall of the trunk section and pivoted in alignment with the said screw 31 in a foot-plate 95 36 fast to said trunk wall. The detail construction of the pivotal pin 31 and associated parts is more clearly seen in Fig. 10, which is a central section of the same in the plane of the rack.

In Fig. 11 I have shown a removable pivot pin 37 for the rack 38 which is held in place by a screw 39 which works in the lower horizontal portion of the bearing member 40 and is recessed at its end to receive the pivot 105 pin, as at 41.

In Fig. 12 the pivotal pin consists of end sections 42, 43 with a spring 44 between them which normally forces them outwardly apart so as to project from the rack 45 and engage bearings in the bearing member 46. A finger piece 47 on one of said end pieces, as 42, projecting through a slot 48 in the sleeve 49 on the rack for said end sections, enables them to be disengaged from the 115 bearing member so that the rack can be removed from the trunk.

Having thus described the invention, what I claim is:—

1. The combination with a trunk, of a 120 support pivoted to the inner wall of the trunk near one end thereof and having a rack adapted to extend transversely across the interior chamber of the trunk section, and brackets upon said rack in spaced substantially parallel relation adapted to receive upon themselves a plurality of garment hangers each having a two-point suspension, said support arranged and adapted to be removed from its bearings with said hangers 125 130

upon said brackets and hung upon a wall or the like.

2. The combination with a trunk, of a support pivoted to the inner wall of the trunk near one end thereof and having a rack adapted to extend transversely across the interior chamber of the trunk section, and fixed brackets on said rack adapted to project therefrom toward the back walls of the trunk section when the support is swung thereinto, said brackets adapted to receive a plurality of garment hangers with a two-point suspension and said support adapted to be removed from its bearings with said hangers upon said brackets and hung upon a wall or the like.

3. The combination with a trunk, of a support pivoted to the inner wall of the trunk near one end thereof and adapted to extend transversely across the interior chamber of the trunk section, said support arranged and adapted to receive a plurality of garment hangers and to be removed from its bearings with said hangers upon it when opened out of the trunk, and means for preventing removal of said support from its bearings when closed into the trunk.

4. The combination with a trunk, of a support pivoted to the inner wall of the trunk near one end thereof and having a rack adapted to extend transversely across the interior chamber of the trunk section, said support arranged and adapted to be removed from its bearings when opened out of the trunk, and brackets upon said rack adapted to receive a plurality of garment hangers and to prevent removal of the support from its bearings when closed into the trunk.

5. The combination with a trunk, of a support pivoted to said trunk and having a rack adapted to swing into the interior chamber of the trunk, and brackets upon said rack adapted to receive a plurality of garment hangers with a two-point suspension, said support arranged and adapted to be removed from its bearings with said hangers upon said brackets and hung upon a wall or the like with said rack flatwise thereagainst.

6. The combination with a trunk, of a support pivoted to said trunk and adapted to swing into the interior chamber thereof, said support arranged and adapted to receive a plurality of garment hangers and to be removed from its bearings with said hangers upon it, and means for releasably locking said support against such removal from its bearings.

7. The combination with a trunk, of a support pivoted to said trunk and adapted to swing into the interior chamber of the trunk, said support arranged and adapted to receive a plurality of garment hangers and to be removed from its bearings with

said hangers upon it when opened out of the trunk, and means for preventing removal of said support from its bearings when closed into the trunk.

8. The combination with a trunk, of a support removably pivoted to said trunk and adapted to swing into the interior chamber thereof, and brackets upon said support adapted to receive garment hangers and to prevent removal of the support from its bearings when swung into the trunk.

9. The combination with a trunk, of a support removably pivoted to said trunk so as to swing into and out of the same, said support having an apertured rack, fixed brackets on said rack projecting laterally therefrom in spaced and substantially parallel relation, and garment hangers having a two-point suspension mounted on said brackets, the said rack adapted to be removed from the trunk with said hangers upon it and hung by means of its apertures upon a wall or the like in flatwise relation thereto.

10. The combination with a trunk, of a support pivoted to said trunk and adapted to swing into the interior chamber of the trunk, said support arranged and adapted to receive a plurality of garment hangers and to be removed from its bearings with said hangers upon it, and a catch upon the trunk opposite the point of pivoting of said support arranged and adapted to engage said support when closed into the trunk and hold it against opening.

11. The combination with a trunk, of a support pivoted to said trunk and having a rack adapted to extend into the interior chamber of the trunk, brackets upon said rack, and hangers each having a cross-piece adapted to hook at its opposite ends over said brackets and depend therefrom.

12. The combination with a trunk, of a support pivoted to said trunk and having a rack adapted to extend into the interior chamber of the trunk, brackets upon said rack adapted to lie adjacent the end or top wall of the trunk substantially parallel thereto, and hangers each having a cross-piece with hooked fingers at the ends thereof adapted to take over said brackets and prevent escape of said hangers when the support is closed into the trunk.

13. The combination with a trunk, of a bearing member mounted upon said trunk and providing opposite aligned bearing studs one longer than the other, a standard having socketed ends adapted to be pivotally inserted on said studs, a rack projecting from said standard, means on said rack for supporting a plurality of garment hangers, and means for locking said standard against escape from its bearing studs.

14. The combination with a trunk, of a bearing member mounted upon the inner

wall thereof near one end and providing opposite alined bearing studs, the one next said end of the trunk being longer than the other, a standard having socketed ends 5 adapted to be pivotally inserted on said studs, a rack projecting from said standard, means on said rack for supporting a plurality of garment hangers, and means for preventing escape of said standard from its 10 bearing studs when the rack is closed into the trunk.

15. The combination with a trunk of a bearing member mounted upon said trunk and providing opposite alined bearing studs one longer than the other and flaring toward 15 its free end, and a support having a standard with socketed ends adapted to be pivotally and removably inserted on said studs, said support adapted to receive a plurality of garment hangers.

NATHAN GOLDSMITH.
